UNITED STATES PATENT OFFICE.

JOSEPH LEON GOBEILLÉ, OF CLEVELAND, OHIO, ASSIGNOR TO ISAAC A. SHEPPARD & CO., OF PHILADELPHIA, PENNSYLVANIA.

DESIGN FOR A HEATING-STOVE.

SPECIFICATION forming part of Design No. 25,421, dated April 21, 1896.

Application filed March 14, 1896. Serial No. 583,263. Term of patent 14 years.

To all whom it may concern:

Be it known that I, JOSEPH LEON GOBEILLÉ, a citizen of the United States, and a resident of Cleveland, Ohio, have invented a certain new and useful Design for a Heating-Stove, of which the following is a specification.

My design for a heating-stove is fully illustrated in the accompanying drawing, which represents the stove in perspective.

The essential feature of the design is the stove, having an enlarged base with ribbed ornamentation thereon combined with scroll-work and having a fluted fire-pot portion and an ornamented body and door.

The base-section A has a wide band at the lower edge, and extending from this band are a series of ribs of different heights, and some of these ribs terminate in curved figures.

The ash-pit door *a* is ornamented by scroll-work. Two of the scrolls extending from the center toward each side are beaded, the rest of the scrolls being plain. The base-section is supported on suitable feet *a'*, having scrolls thereon in keeping with the design of said section.

Mounted on the base is a foot-rail *a'*, also ornamented in keeping with the base. The fire-pot section B is ornamented by a series of vertical ribs. The body-section C is ornamented by a series of interlaced scrolls. The fire-door *c* is made in two parts *c' c'*, the lower part *c'* having a panel bordered by scroll-work, and below the panel are a series of interlaced

scrolls. The upper section *c'* of the door has a series of scrolls forming extensions of the 35 scrolls on the lower part of the door.

The dome-section D has a plain wide band *d* at the base, having an undulating upper edge, and between this band and a plain band *d'* are scrolls. The dome proper, *d'*, is of a 40 form in keeping with the main features of the design.

I claim—

1. The design for a heating-stove as herein described and as shown in the accompanying 45 drawing.

2. The design for a body portion of a heating-stove as herein described and as shown in the accompanying drawing.

3. The design for the base of a heating- 50 stove as herein described and as shown in the accompanying drawing.

4. The design for the fire-door of a heating- 55 stove as herein described and as shown in the accompanying drawing.

5. The design for the ash-pit door of a heating-stove as herein described and as shown in the accompanying drawing.

In testimony whereof I have signed my name to this specification in the presence of 60 two subscribing witnesses.

JOSEPH LEON GOBEILLÉ.
